UNITED STATES PATENT OFFICE.

JAMES F. LOUCKS, OF CLEVELAND, OHIO, ASSIGNOR TO HOLORIB, INC., OF CLEVELAND, OHIO, A CORPORATION OF OHIO.

CLAMPING DEVICE.

Application filed October 18, 1926. Serial No. 142,319.

This invention relates to clamping devices and, while capable of use in other relations, is peculiarly adapted for the purpose of securing to metal beams sheet-metal structural units of the general type shown in the patent to Harry Gillett and myself issued February 23, 1926, No. 1,574,586. The general object of the invention is to provide a simple, economical and efficient clamp which will enable metal sheets to be secured to structural beams and in spaced relation thereto.

15 Further and more limited objects of the invention will appear hereinafter and will be accomplished and realized in and through the construction and arrangement of parts shown in the drawings, wherein Fig. 1 represents a sectional view through a sheet metal structure showing the same secured to a beam by means of clamps embodying my invention; Fig. 2 a plan view of the beam and one of the clamps shown in Fig. 1; Fig. 3 a detail in section through the structural beam and metal sheet, showing one of the clamps in section; and Fig. 4 a detail in perspective of one of the clamps.

Describing the various parts by reference characters, 1 denotes the web and 2 a flange of a built-up angular beam, the flange of said beam being a channel member having a flange 2^a at one edge adapted to engage one side of the web 1 and to be secured thereto in any convenient manner, as by welding, the outer flange of the channel member being indicated at 2^b. Supported on top of the said beam is a building-construction unit, the same comprising a metal sheet 3 having hollow ribs 4 projecting downwardly therefrom, each of the said ribs being triangular in section and the tops of the ribs being substantially closed, whereby the upper surface of the sheet 3 will be substantially continuous or uninterrupted, while the bottom of the sheet will be provided with triangular ribs which are adapted to be supported on the tops of structural beams. The details of construction of the said unit and the purposes and advantages of the same are fully set forth in the aforesaid patent, the clamping means shown herein being especially useful for securing units or sheets of this general character to structural beams upon which they are supported by the hollow ribs.

Each clamp is made of sheet metal and comprises generally a base portion which is adapted to rest upon the top of the beam.

with a post struck from the base portion, intermediate the ends of the latter, the said post being provided with a tongue for securing the post to and beneath the metal sheet, one end of the base member being formed into a hook which is adapted to be applied to the edge flange ^{2b} of the structural member while the opposite end is adapted to be bent down over the upper end of the web 1. 60

5 denotes the base of one of my clamping members, the said base being adapted to rest on top of the beam. Projecting upwardly from the said base, intermediate the ends thereof, is a post 6 having a central tongue 7 provided with a point 7^a, there being a shoulder 8 at the bottom of the tongue 7, on each side thereof.

One end of the base 5 comprises a vertical portion 9 and a pair of upwardly and inwardly inclined legs 10, the legs being conveniently formed by removing the metal from the lower part of the depending portion 9 prior to bending upwardly the legs thus formed. The part 9 is considerably deeper than the edge flange 2^b with which it cooperates. This extra depth of the part 9 and the upward and inward inclination of the legs 10 enable the open hook provided between such legs and the part 9 to be slipped around and under the flange 2^b and the body of the clamp to be swung around until the base 5 rests upon the beam flange 2, after which the legs 10 may be driven or hammered upwardly and outwardly so as to engage the under surface of the beam flange 2 and the inner surface of the flange 2^b, the end of the base which is opposite the parts 9 and 10 being bent downwardly into engagement with the top of the web 1, to form a clamping flange shown at 5^a. 55

It will be noted that, when the clamp is in place upon the beam, the bottom of the hooked part 9, 10, does not engage the bottom of the edge flange 2^b, due to the depth of the part 9. 100

After the clamps have been applied to the beam, the sheets 3 are then applied to the tops of the clamps. With a suitable punch, the sheets will be driven down upon the tongues 7 and into engagement with the shoulders 8, 105 after which the tongues will be bent over and flattened down, as shown in Figs. 1 and 3.

It is preferred that the posts 6 to the shoulders 8 shall be of slightly less height than the depth of the ribs 4 whereby the sheets 3 will 110

be drawn down slightly into engagement with the shoulders, thus giving a firmer hold of the sheet upon the beams.

The base 5 will be of sufficient length to accommodate considerable variations in the widths of the tops of the beams to which the clamps are applied, this length enabling clamping flanges 5^a of varying depth to be struck from such base, the depth of such flanges depending upon the width of the beams to which the clamps are applied.

For convenience of description, the sheets 3 are assumed to be applied to the tops of the structural beams, with the clamping members resting on top of the beams and interposed between the same and the lower surfaces of the said sheets; and the terms "upper" and "lower" have been employed in the description and claims to indicate the relative positions of the parts, but without any intention thereby of limiting my invention to a construction wherein the positions of the beams and of the sheets may not be other than those specifically shown and described herein.

Having thus described my invention, what I claim is:

1. A sheet metal clamping member for securing a metal sheet to and in spaced relation from a beam, the said member comprising a base adapted to rest on the upper surface of such beam, said base having struck therefrom and intermediate the ends thereof an upwardly extending post provided with a tongue projecting from the top thereof with shoulders

on each side of the base of said tongue and spaced from the said base, there being a hook depending from one end of the base which is adapted to be applied to a depending flange on said beam and to engage the opposite faces of such flange, the base being of such length as to enable a flange to be bent from the end which is opposite such hook into engagement with the opposite side or edge of the said beam.

2. A sheet metal clamping member for securing a metal sheet to and in spaced relation from a beam, the said member comprising a base adapted to rest on the upper surface of such beam, said base having struck therefrom and intermediate the ends thereof an upwardly extending post provided with a tongue projecting from the top thereof with shoulders on each side of the base of said tongue and spaced from the said base, there being a hook depending from one end of the base, the said hook comprising a vertical member adapted to engage the outer face of a depending flange of said beam, a pair of legs extending from said member and adapted to be bent into engagement with the inner face of said flange, the base being of such length as to enable a flange to be bent from the end thereof which is opposite such hook into engagement with the opposite side or edge of the said beam.

In testimony whereof, I hereunto affix my signature.

JAMES F. LOUCKS.
